ELECTRIC CONNECTER AND RECEPTACLE
THEREFOR

Wilson D. Craig Wright, Princeton, N. J.

Application January 7, 1936, Serial No. 57,901

6 Claims. (Cl. 173—330)

This invention relates, generally, to electrical plugs such as used in connection with domestic electrical appliances and for other uses, and the invention has reference, more particularly, to a novel construction of electrical plug and cooperating receptacle therefor.

Electrical plugs as heretofore generally constructed usually consist of two flat, spaced prongs projecting from the plug body, the said 10 prongs being adapted for insertion into conforming recesses provided in the plug receptacle. These prongs or tongues have outer flat ends and must be aligned with the receptacle openings before they can be inserted thereinto. Owing to 15 necessity of aligning the plug prongs with the receptacle apertures before the plug can be engaged in the receptacle, considerable effort and patience is usually required when thusly connecting appliances to a service line. This is especially true when a receptacle is located in a 20 baseboard, for in such case the user must stoop over and endeavor to locate the recesses in the receptacle and place the plug prongs therein and very often, owing to poor light, this is almost 25 impossible. Furthermore, the prongs of plugs heretofore used are relatively weak and easily bent so the same, as a result of accidental bending, will not properly fit into the receptacle and for this reason much time is often lost in trying 30 to insert a plug.

The principal object of the present invention is to provide a novel electrical plug and associated receptacle that overcomes the above defects. The plug and receptacle of this invention being 35 constructed and arranged for extremely simple and easy insertion of the plug into the receptacle and without the necessity of aligning the plug prongs with the receptacle recesses.

Another object of the present invention lies in 40 the provision of the novel plug and cooperating receptacle of the above character wherein the prongs taken as a whole are of substantially cruciform shape and are provided with conical tapered or somewhat pointed outer end portions 45 for easy engagement into a conforming conical depression provided in the receptacle face, whereby the plug is rendered self centering with respect to the receptacle and then may be turned, if necessary, to secure the proper engagement 50 of the plug prongs in the receptacle recesses, the operation of plugging in being extremely simple, easy and quick and not requiring a clear view of the receptacle to obtain the desired end.

Another object of the present invention is to 55 provide a novel electrical plug and receptacle

therefor of the above character that is of extremely rugged and durable construction, the prongs of the plug being so constructed as to strongly resist any bending thereof, and the receptacle being so constructed as to render the same substantially fool proof, the contacts of the receptacle being disposed to reduce the possibility of their accidental or intentional shorting to a minimum.

Other objects of this invention, not at this 10 time more particularly enumerated, will be clearly understood from the following detailed description of the same.

The invention is clearly illustrated in the accompanying drawing, in which:—

Fig. 1 is a view in front elevation of the novel receptacle of this invention;

Fig. 2 is a view in side elevation of the novel plug of this invention;

Fig. 3 is a view similar to Fig. 2, but with the 20 plug turned through 90°;

Fig. 4 is a view in front elevation of the plug;

Fig. 5 is a fragmentary sectional view showing a plug inserted into the receptacle, the latter being mounted for use;

Fig. 6 is a view in front elevation of a portion 25 of the structure shown in Fig. 5;

Fig. 7 is a sectional view taken substantially on line 7—7 in Fig. 6.

Similar characters of reference are employed 30 in said views, to indicate corresponding parts.

Referring now to the said drawing, the reference numeral 1 designates a plug having an insulating plug body 2 shown as provided with a finger grip portion 3. Plug 1 is provided with 35 two prongs 4 and 5 that cross one another at right angles, each of said prongs extending for the greater portion of the diameter of the plug body 2. The prongs 4 and 5 are preferably stamped or pressed from sheet metal and each 40 of these prongs consists of two parallel, spaced prong legs that are integrally interconnected by a bridge member or yoke, the bridge members of the prongs being so disposed as to cross one above the other so that the two prongs do not 45 touch at any point. Thus the prong 4 has prong legs 6 and 6' and a bridge member 7, whereas the prong 5 has prong legs 8 and 8' and a bridge member 9, the bridge member 9 passing over the bridge member 7 and spaced from the latter. 50

The prong legs of each of the prongs 4 and 5 are provided with base lugs 11 and 11' extending at right angles to the prong legs and in opposite directions with respect to each other. The base lugs 11 of the prongs 4 and 5 are secured to the 55

plug body 2 as by hollow rivets 12 that may be molded or otherwise fixed in the plug body, thereby rigidly mounting the prongs 4 and 5 in fixed position upon the plug body. The base lugs 5 11' are threaded for receiving screws 13 that serve to attach or hold the leads 14 and 14' to the respective prongs. If desired, the screws 13 may thread into the plug body 2, thereby further securing the prongs upon the plug body, or 10 the base lugs 11' may also be secured to the plug body as by hollow rivets and into which the screws 13 may thread, if desired.

Owing to the relatively great width of the prongs 4 and 5 and to the fact that their base 15 lugs 11' and 11 extend in opposite directions, these prongs are very strong and rigid and for that reason can stand much abuse without bending or becoming loose from the plug body 2. The apertures 15 and 16 provided in prongs 4 and 5, 20 respectively, inwardly of the bridge members 7 and 9 and extending between the prong legs provide ample space for receiving the leads 14 and 14' drawn through the hollow plug body 2 and enable the ready insertion of these leads under 25 the holding screws 13.

The outer end portions of the prongs 4 and 5 are conically tapered at 18 and 18' respectively, the prong 5 coming to a point at 17 in line with the longitudinal axis of the plug. The tapered 30 portions 18 and 18' are also preferably beveled or rounded in the direction of the thickness of the prongs so as to eliminate sharp corners that might tend to mar the plug receptacle in use.

The plug receptacle 20 is of insulating material and is provided in its forward exposed face with a conical depression 21 for conformably receiving the conical outer end portions of prongs 4 and 5, the taper of depression 21 being the same as those of the prong ends. Receptacle 20 40 is provided with a cruciform prong receiving recess 22 disposed concentrically with depression 21 for receiving the prongs 4 and 5. The prong receiving recess 22 thus has four branches and in two of these branches extending at right angles 45 to one another are provided stationary spring contact members 23 for engaging the prongs 4 and 5. Contact members 23 are connected as by jumpers 24 to supply leads 25. The plug receptacle 20 is carried as by a saddle member 26 50 that may be attached as by screws 27 to a supporting wall or other structure.

In use, to insert the plug 1 into the receptacle 20 it is merely necessary to insert the conically tapered outer end portions of the prongs into the 55 conical depression 21, the cooperating conical surfaces, serving to automatically center the plug with respect to the receptacle. If the prongs happen to be aligned with recess 22 they will directly enter this recess, thereby completing the 60 engagement of plug and receptacle, the prongs engaging contacts 23. If the prongs are not initially aligned with the recess 22, the plug 1 may be given a slight twist in either direction, whereupon the prongs will enter this recess.

65 It will be noted that the plug may be inserted in any one of four positions into the receptacle recess 22. Inasmuch as the stationary contacts 23 are disposed in right angled branches of the recess 22, the insertion of a piece of metal into 70 one of the cross slots of the receptacle will not short the circuit, thereby rendering the device substantially fool proof. If in any event the prongs 4 and 5 should become bent and touch each other, it will be impossible to insert them

into recess 22 until they are again straightened out.

As many changes could be made in the above construction and many apparently widely different embodiments of this invention could be made without departing from the scope thereof, as defined by the following claims, it is intended that all matter contained in the above description or shown in the accompanying drawing shall be interpreted as illustrative and not in a limiting 10 sense.

I claim:

1. In a device of the character described, an electrical plug having a plug body, and a pair of intersecting prongs carried by said plug body, 15 said prongs being insulated from one another, each of said prongs consisting of spaced prong legs that are rigidly interconnected adjacent their outer free ends to give the prong great strength.

2. In a device of the character described, an electrical plug having a plug body, and a pair of intersecting prongs carried by said plug body, 20 said prongs being insulated from one another, the prong assembly having a substantially cruciform shape, and with the outer end of the same conically tapered to facilitate its insertion into a receptacle, the outer tapered surfaces of the individual prongs lying in a common conical surface.

3. In a device of the character described, a plug and plug receptacle, said plug having a pair of contact members disposed to present a cruciform appearance, the outer end portions of said contact members being tapered so as to lie 35 in the surface of an imaginary cone, said receptacle having a conical depression in its face for conformably receiving said contact member end portions, and a receptacle recess of cruciform shape disposed concentrically with said conical depression, said cruciform recess having contact members therein disposed at right angles to each other.

4. In a device of the character described, a plug and plug receptacle, said plug having a pair 45 of contact members disposed to present a cruciform appearance, the outer end portions of said contact members being tapered so as to lie in the surface of an imaginary cone, said receptacle having a conical depression in its face for conformably receiving said contact member end portions, and a receptacle recess of cruciform shape disposed concentrically with said conical depression, said cruciform recess having stationary contact members disposed in branches thereof extending at right angles to one another.

5. In a device of the character described, an electrical plug having an apertured plug body, and a pair of intersecting prongs carried by said plug body, each of said prongs comprising spaced parallel prong legs and an outer interconnecting bridge member, the spaces between said prong legs providing a passage, whereby leads may be drawn through said apertured plug body, between 60 said legs and attached to said prongs.

6. In a device of the character described, an electrical plug having an apertured plug body, and a pair of intersecting prongs carried by said plug body, each of said prongs comprising spaced parallel prong legs and an outer interconnecting 70 bridge member, the bridge member of one of said prongs being positioned outwardly of the bridge member of the other prong.

WILSON D. CRAIG WRIGHT.
